CORNER CONSTRUCTION

Walter E. Rose, Chicago, Ill., assignor, by mesne assignments, to Container Supply and Research Co., Dundee, Ill., a corporation of Illinois

Application June 6, 1955, Serial No. 513,337

7 Claims. (Cl. 217—65)

The present invention relates to a container and has special reference to a corner construction forming a part of said container.

More particularly, this invention relates to a shipping container of the knock-down type, comprising corner constructions, panels removably connected to said corner constructions forming the sides of the container, a top and a bottom or base. With the present corner construction the containers may be quickly and easily assembled. The corner construction determines the height of the containers, but the other dimensions depend upon the size of the panels, top and base employed with the corner constructions. Thus, containers of various sizes and shapes may be formed from a single set of corner constructions through the use of different sized panels, tops and bases.

The present containers are particularly suitable for packing and shipping bulky articles, such, for example, as major household appliances. If desired, they may be assembled about the article to be packed. After being assembled, the containers may be maintained in assembled position by metal straps, although other securing means, such as staples or nails, may be employed for this purpose.

The corners provide great strength, particularly longitudinally thereof, and the assembled containers protect their contents against the roughest type of treatment and handling. If strapped or wire bound, the container may be easily taken apart to remove the article packed therein after the removal of the metal straps or wires, and the parts of the container can be used again to form a container or a different article.

An object of the present invention is to provide a strong container which may be employed for shipping appliances and other bulky articles.

Another object of the invention is to provide a container of the knock-down type.

A further object of the invention is to provide a knock-down container which may be easily and quickly assembled and taken apart with a minimum of defacement of the members comprising the container.

Still another object is to provide a knock-down container which may be assembled into a number of sizes and shapes from a relatively few parts.

An additional object is to provide a corner construction for a knock-down container having high strength.

Further objects and advantages will be apparent from the following description and claims when considered with the accompanying drawings, in which:

Fig. 1 is a perspective view of a container embodying the present invention;

Fig. 2 is a cross-sectional view of a corner of the container shown in Fig. 1 taken on the line 2—2 thereof;

Fig. 3 is a cross-sectional view similar to that of Fig. 2 showing a modified corner construction;

Fig. 4 is a perspective view of a forming tool for assembling and holding the corner construction shown in

2

Fig. 2, with the various parts of the corner in the process of being assembled; and

Fig. 5 is a partial perspective view of the container skid base.

Referring more particularly to the drawings, there is shown in Fig. 1 thereof a container embodying the present invention comprising corner constructions 11 with panels 12 arranged between the corner constructions and connected thereto, a top closure member 13 and a skid base 14. The top and base may be of any desired construction.

In the present container the corner constructions 11 and side panels 12 are preferably made of laminated fibrous material of the type described in Randall et al. Patent No. 1,997,344, dated April 9, 1935. The composite material of this patent consists of an intermediate layer of wood veneer thin enough to flex readily in one direction, and heavy kraft or other paper sheets adhesively secured to both sides of the layer of wood veneer, with the fibers of the paper cover sheets running generally transversely of the grain of the layer of wood veneer. This laminated fibrous material may be readily bent without breaking. When this composite material is employed, it is arranged so that the wood grain runs longitudinally of the corners. While laminated material of the type disclosed in Patent No. 1,997,344 is preferably employed, any other suitable material having the requisite strength and flexibility may be employed.

The corner constructions shown in Figs. 2, 3 and 4 are formed from strips of suitable material. Corner constructions of the type illustrated in Fig. 2 consist of three layers. The outer layer 14 is preferably arcuate or rounded in cross section, the intermediate and inner portions 15 and 16, respectively, are nested therein. The inner layer 16 preferably consists of a substantially flat longitudinally extending central portion 17 with two side portions or wings 18 extending inwardly at an angle therefrom. The intermediate member 15 has a longitudinally extending flat central portion 19, somewhat wider than the central portion 17 of the inner member 16, with wing members 21, narrower than the wing portions 18 of the inner member 16, extending inwardly at an angle to the central portion 17.

In forming a corner construction of the type shown in Fig. 2, the intermediate member 15 and inner member 16 are preferably scored or creased and/or pressure bent longitudinally to form the central portion 17 and wing portions 18 of the inner member, and the central portion 19 and wing portions 21 of the intermediate member 15. Thereafter the two members 16 and 15, after having their central portions stapled or otherwise secured together, are arranged in nested position in the outer member 14, as shown in Figs. 2, 3 and 4. The inner member 16 and the outer member 14 are substantially the same width, although for some purposes it may be desirable to have the inner member 16 slightly wider. Accordingly, when the three members are arranged in assembled position, the outer edges of the inner and outer members extend outwardly beyond the edges of the wings 21 of the intermediate member 15. The three members are then secured together by any suitable means, such as staples 22, adjacent the outer edges of the intermediate member 15. As shown in Fig. 1, the staples 22 are preferably closer together near the middle portion of the corner constructions. The thickness of the intermediate member 15 is preferably the same or slightly less than the thickness of the panels 12 to be used therewith. With this construction the edges of the inner and outer members outwardly of the intermediate member form slots or grooves which converge toward the outer edges thereof for receiving the panel edges therein.

While the corner constructions illustrated are right angle corners, the angularity of the sides of the corners may be varied dependent upon the shape of the completed container. However, with a right angle corner construction such as that illustrated, the two wing portions 18 of the inner members 16 are at an angle slightly greater than 90 degrees, while the side portions of the outer curved member 14 are at an angle slightly less than 90 degrees. The amount of convergence of the slots formed at each side of the corner construction may be increased by increasing the width of the central portion 19 of the intermediate member 15, by decreasing the width of the middle portion 17 of the inner member or by stapling closer to the outer edges of intermediate member 15. In any corner construction the angle between the wing portions 18 of the inner member is greater than the angle between the edge portions of the outer member 14.

The corners may be readily assembled through the use of a form or tool 23, such as illustrated in Fig. 4. This shaping form has a central raised portion 24 of the intended shape of the inner strip 16. Upwardly extending side portions 25 at opposite sides of the central raised portion 24 have merged slots 26 and 27 therein for receiving and holding in proper position the edges of the inner and outer strips 16 and 14. As the intermediate strip 15 is stapled to the inner strip 16, it is held in proper position between the inner and outer strips. Thereafter all three members are secured together by staples 22 as shown in Figs. 2 and 3.

It may frequently be desirable to provide an extra strong container. Many times heavy articles are packed in the containers which are then stacked vertically one on top of the other. It is then necessary to insure that the container will withstand large vertical compression.

This may be accomplished in the present container by providing the corner constructions with longitudinal inserts 28 preferably of substantially the same length as the length of the corner constructions in the space between the central arcuate portion of the outer member 14 and the opposed substantially flat central portion 19 of the intermediate member 15. The inserts which may be made of wood with the grain running longitudinally thereof or of any other suitable material may be inserted during formation of the corner construction in a form such as shown in Fig. 4, or after the corner construction, such as shown in Fig. 2, is formed. If the inserts 28 are not employed, it may be desirable to insert short inserts of the same cross-sectional shape at the strapping points to prevent crushing of the corners when the horizontal straps are secured about the container.

The base of the container may be a suitable skid such, for example, as that shown in Figs. 1 and 5. This base skid consists of two main side members 32 and 33 upon which the skid rests connected together by cross members 34 and 35 adjacent the ends of the side members and, if desired, one or more intermediate transverse members 36 may also be employed. Longitudinally extending positioning members 37 and 38 are also mounted on the side members 32 and 33 and abut the end transverse members 34 and 35. The outer periphery of the positioning members 37 and 38 and the end transverse members 34 and 35 lies inwardly of the ends and outer sides of the main supporting members 32 and 33 and forms a frame about which the corner members 11 and panels 12 may fit while resting on the main supporting members 32 and 33. The outer corners of the end cross members 34 and 35 are mitered so that the corner members 11 may fit thereover.

To form a container such as shown in Fig. 1, two of the corner members or constructions 11 are first connected by inserting a panel 12 of desired size in the slots of the adjacent sides of the two corner members. Due to the converging form of these slots, the panels will be gripped therein. In a similar fashion, the additional corner constructions and panels are secured together. These

initially may be arranged about the bottom skid or base member 31, on which the article to be packed is resting, or the sides and corners may be first assembled independently of the base and thereafter positioned about the base and finally the top closure member 13 secured thereon. To hold the container in assembled position, metal straps or wire may thereafter be secured horizontally and vertically about the container as desired. The length or height of the panels is preferably slightly less than the length of the corner constructions with which used.

The width of the panels employed is preferably such that the vertical edges of the article being packed, for example, a freezer, will abut the substantially flat central portions 17 of the corner constructions. In this manner the article will remain tightly in place with only the corners thereof engaging the portions 17 of the corner members or a protective padding thereover while the sides of the article will be somewhat spaced from the wings 18 and the panel members 12 intermediate the corners. However, if desired, the article may be spaced from the corners as well as the panels of the container.

The corner constructions provide great longitudinal strength for the container and not only may securely hold the article therein in proper position, but as the corners of the container are subjected to most of the rough treatment, they further protect the article even without the inserts 28. The arcuate body portion of the outer member 14, intermediate the sides of the flat central portion 19 of the intermediate member, will withstand extreme force and heavy blow because of the shape of the members and the fact that the outer member is spaced a substantial distance from the intermediate member. Also, due to this space there is little likelihood of nails or other sharp objects penetrating the corner and contacting the article packed therein.

The containers of the present invention can be very quickly and easily assembled from the corner constructions 11 and the panels 12, together with the top closures and bases of proper shape. The container, when assembled and secured such as by means of metal straps or wires, is extremely strong and will withstand hard rough usage while holding the article packed therein in desired position and safe from injury.

While particular embodiments of this invention have been illustrated and described, it will be understood, of course, that the invention is not to be limited thereto since many modifications may be made, and it is contemplated, therefore, by the appended claims to cover any such modifications as fall within the true spirit and scope of this invention.

I claim:

1. A corner construction for a container having side panels comprising a pair of longitudinally extending strips of stiff resilient material concave in cross section arranged one within the other, spacing means securing said strips together at a distance from their longitudinal edges in spaced relation forming a slot at each side outwardly of said securing means of a size to receive therein one edge of a panel, the inner of said strips having its longitudinal edge portions at a greater internal angle to each other than the angle between the longitudinal edge portions of the outer of said strips to form outwardly converging slots.

2. A corner construction for a container having side panels comprising a pair of longitudinally extending strips of stiff resilient material concave in cross section arranged one within the other, spacing means positioned between said strips a distance inwardly from the longitudinal edges thereof for holding said strips apart a distance to receive therebetween an edge of a side panel, and securing means for securing said strips together a distance from their longitudinal edges; the inner of said strips having its longitudinal edge portions at a greater internal angle to each other than the angle between the longitudinal edge portions of the outer of said strips to

form outwardly converging slots at each side of said strips outwardly of said spacing means.

3. A corner construction for a container having side panels comprising outer, inner and intermediate longitudinally extending strips of stiff resilient material, said outer strip being substantially arcuate in cross section, said inner strip having a substantially flat central portion and wing portions at each side thereof at an angle thereto for fitting within said outer strip, said intermediate strip being of substantially the same thickness as a side panel and having a substantially flat central portion slightly wider than the central portion of said inner strip with wing portions at each side thereof at an angle thereto, said intermediate strip being substantially narrower than the inner and outer strips and positioned therebetween, with its outer edges inwardly of the outer edges of said inner and outer strips, and securing means for securing said strips together adjacent the longitudinal edges of said intermediate strip with the outer edge portions of said inner and outer strips converging to form outwardly converging slots outwardly of said intermediate member.

4. A corner construction for a container having side panels comprising outer, inner and intermediate longitudinally extending strips of stiff resilient material, said outer strip being substantially arcuate in cross section, said inner strip having a substantially flat central portion and wing portions at each side thereof at an angle thereto for fitting within said outer strip, said intermediate strip being of substantially the same thickness as a side panel and having a substantially flat central portion slightly wider than the central portion of said inner strip with wing portions at each side thereof at an angle thereto, said intermediate strip being substantially narrower than the inner and outer strips and positioned therebetween with said central portion contacting the central portion of the inner strip and the edges of the opposite side of said intermediate strip central portion engaging said outer strip, and securing means for securing said strips together adjacent the longitudinal edges of said intermediate strip with the outer edge portions of said inner and outer strips converging to form outwardly converging slots outwardly of said intermediate member.

5. A corner construction for a container having side panels comprising outer, inner and intermediate longitudinally extending strips of stiff resilient material, said outer strip being substantially arcuate in cross section, said inner strip having a substantially flat central portion and wing portions at each side thereof at an angle thereto for fitting within said outer strip, said intermediate strip being of substantially the same thickness as a side panel and having a substantially flat central portion slightly wider than the central portion of said inner strip with wing portions at each side thereof at an angle thereto.

said intermediate strip being substantially narrower than the inner and outer strips and positioned therebetween with said central portion contacting the central portion of the inner strip and the edges of the opposite side of said intermediate strip central portion engaging said outer strip, a longitudinally extending stiff strong insert positioned and shaped to fit between the flat central portion of said intermediate strip and arcuate outer strip outwardly thereof, and securing means for securing said strips together adjacent the longitudinal edges of said intermediate strip with the outer edge portions of said inner and outer strips converging to form outwardly converging slots outwardly of said intermediate member.

6. A container comprising a plurality of corner constructions and panels therebetween and connected thereto, each of said corner constructions comprising a pair of longitudinally extending strips of stiff resilient material concave in cross section arranged one within the other, a spacing strip of substantially the same thickness as a panel positioned between said first mentioned strips and having its outer edges spaced a distance inwardly from the edges of said first mentioned strips, and securing means for securing together said first-mentioned strips and said spacing strip adjacent the edges of said spacing strip, the inner of said strips having its longitudinal edge portions at a greater internal angle to each other than the angle between the longitudinal edge portions of the outer of said strips to form a converging slot at each side of said strips outwardly of said spacing strip, and said panels having opposite sides of substantially the same length as the length of said corner constructions with said sides inserted in the slots in adjacent corner constructions.

7. A container comprising a plurality of corner constructions and panels therebetween and connected thereto, each of said corner constructions comprising a pair of longitudinally extending strips of stiff resilient material concave in cross section arranged one within the other, said strips being secured together at a distance from their longitudinal edges a distance apart substantially equal to the thickness of a panel forming a slot at each side outwardly of said securing means, the inner of said strips having its longitudinal edge portion at a greater internal angle to each other than the angle between the longitudinal edge portions of the outer of said strips to form outwardly converging slots, and said panels having opposite sides of substantially the same length as the length of said corner constructions with said sides inserted in the slots in adjacent corner constructions.
